[57] CLAIM

The ornamental design for a vertical short takeoff and landing aircraft, as shown and described.

DESCRIPTION

FIG. 1 is a top plan view of a vertical short takeoff and landing aircraft showing my new design;

FIG. 2 is a front elevational view thereof;

FIG. 3 is a left side elevational view thereof;

FIG. 4 is a bottom plan view thereof; and

FIG. 5 is a rear elevational view thereof.
